FIG. 2

FIG. 3

FIG. 4

FIG. 1 is a front perspective view of a truck bumper showing my new design;

FIG. 2 is a top plan view thereof;

FIG. 3 is a bottom plan view thereof; and

FIG. 4 is a rear elevational view thereof, it being understood that the vertical channel has been broken away at the center for convenience of illustration.

The surface pattern which has been fragmentarily depicted in FIGS. 1 and 2 is understood to be continuous throughout the areas shown.

I claim:

The ornamental design for a truck bumper, as shown and described.
